UNITED STATES PATENT OFFICE.

IVAN ARKLEY BAYLEY, OF NORTH SYDNEY, NOVA SCOTIA, CANADA.

FREIGHT-TRANSPORTER.

1,230,838.

Specification of Letters Patent. Patented June 26, 1917.

Application filed August 11, 1916. Serial No. 114,353.

To all whom it may concern:

Be it known that I, IVAN ARKLEY BAYLEY, a citizen of Canada, residing at North Sydney, Nova Scotia, Canada, have invented a 5 certain new and useful Improvement in Freight-Transporters, of which the following is a full, clear, and exact description.

My invention relates to an improvement in freight transporters, and has for its object 10 to provide a huge transporter constructed of steel framing with or without covering and partitioning plates adapted to carry commercial timber or logs or other freight and bound together in a peculiar manner so 15 that large amounts of timber or other freight, etc., can be safely transported from one point to another. Heretofore, timber rafts having an average length of 700 feet, with a thickness or height of approximately 20 30 feet and a breadth of 55 feet, have been constructed by placing logs in proper position and binding the same together by encircling chains. The chains, however, are very expensive and if any break occurs the 25 raft is liable to largely, if not entirely, disintegrate. Moreover, at the end of the journey, when the raft is broken up, the chains have to be sold at a figure much below their cost or transported at large expense to a 30 place where they can be again used for another raft. One of the objects of my invention is to provide a raft in which the binding material can be sold at the end of the journey for approximately what it cost, and 35 also to provide a raft which is not liable to disintegrate and which, if broken up, will divide into a number of subdivisions, each constituting separate rafts. A further object of my invention is to provide a trans- 40 port made up of closed spaces within the general framework for carrying various kind of freight, including merchandise, oil, molasses, etc.

The following is description of an em- 45 bodiment of my invention, reference being had to the accompanying drawing, in which,

Figure 1 shows a side elevation of a raft embodying my invention;

Fig. 2 is a transverse section of the same 50 on the line 2-2, Fig. 1, on an enlarged scale, the timber being omitted for the most part;

Fig. 3 is a vertical longitudinal section of the frame on the line 3-3, Fig. 2;

Fig. 4 is a horizontal section of the frame 55 on the line 4-4, Fig. 2;

Fig. 5 is a vertical longitudinal section of the frame on the line 5-5, Fig. 2;

Fig. 6 is a detail section on the line showing two elements, the proportions being enlarged;

Fig. 7 is an enlarged detail of parts showing a longitudinal section of a modified form of compartment; and

Figs. 8, 9 and 10 are side, end and plan views of a manhole and cover.

Referring more particularly to the drawings, 1-1-1, etc., Fig. 4, are iron rods lying in a horizontal plane and constituting a longitudinal series extending from the bow to the stern of the raft. There are a plurality of such series, each arranged above the other as indicated in Fig. 2. 2-2-2, etc., Fig. 4, are longitudinally extending rods constituting a series extending transversely from one side of the raft to the other. As 70 appears in Fig. 2, there are a plurality of such series lying one above the other. The rods of each transversely extending series lie close to the plane of the rods of one of the longitudinally extending series and where 75 the rods of the two series come in contact they are properly secured together, preferably by welding, which can be done by means of an oxy-acetylene torch. 3-3-3-3, etc., Fig. 3 are vertical rods constituting a longitudinal extending vertical series. There 80 are a plurality of such series, as is shown in Figs. 2 and 4. The rods making up these vertical longitudinally extending series make contact with rods of the horizontal longitudinal series and horizontal transverse series, and where they make contact are secured thereto by welding or other means 85 as above described.

It will be seen from the foregoing that the 90 vertical rods, together with the transverse rods and the longitudinally extending rods, provide six kinds of series; (1) transversely extending series of vertical rods, (2) longitudinally extending series of vertical rods, 100 (3) transversely extending series of horizontal rods, (4) longitudinally extending series of horizontal rods, (5) vertically extending series of longitudinal rods, and (6) vertically extending series of transverse rods. The longitudinal spaces between the 105 longitudinal extending series of vertical rods and the longitudinally extending series of horizontal rods are shown in the drawings to be largely filled with the logs or timber 5 to 110

be transported, which is thus held securely in place, the rods of the two kinds of series last referred to being held from movement in a direction parallel to the axes of the timber by the longitudinally extending rods. 5 A series of encircling rods 4—4—4, etc., is also provided which holds the outer layer of timber in place. This series extends longitudinally. In order to brace the rods, I 10 provide a series of rods 6 and a series of rods 7 placed at angles to one another, and also at an angle to the vertical rods 3. These rods 6 and 7 lie in planes parallel with vertical longitudinally extending series and in contact with the rods of such series. Whenever 15 they come in contact with rods of such series they are secured thereto by welding or otherwise so as to brace the raft. I also provide horizontal braces consisting of rods disposed 20 in a similar manner relatively to rods in a horizontal longitudinally extending series, and secured to contacting rods of that series. In order to provide suitable draft rods, I 25 make five of the longitudinal rods of heavier material, as indicated at 2'—2'—2'—2'—2', Fig. 2, and provide these rods at their forward ends with loops to which cables or hawsers 8 are connected. These looped rods extend throughout the length of the raft so 30 as to distribute the pulling strain throughout the length of the raft, being secured to any vertical or transverse rod with which they come in contact.

In making a raft 300 feet by 50 by 50, I 35 place the series of rods 1, 2 and 3 about five feet apart and make the rods of five-eighths of an inch round mild steel. The rods 4 are of the same size, while the rods 2' are one inch or more in diameter. The exposed ends 40 of any rods where they are adjacent to other rods, are preferably bent as shown in Fig. 6 so as to make a stronger connection, reinforcing the welding. The rods at the start need not be of full length, since they can be 45 extended as desired by welding on additional sections.

In order to provide compartments for oil, cotton or other merchandise, I weld sheets of metal 9, 10 and 11 to the bars, of suitable 50 horizontal vertical and transverse series as shown in Figs. 3 and 4, providing suitable manholes 12 for the same. Some of the transverse or vertical rods may be omitted 55 from these compartments so as to conform to the size or shape of the freight packages.

In constructing a timber raft, portions of the encircling bars are first laid in place and portions of the vertical rods are then secured thereto, the lower longitudinal rods preferably being also put in place and secured to rods with which they contact. Long logs of timber are then laid between the longitudinal series of vertical rods until a thickness of about five feet is attained. Transverse 65 rods are then put in place and also a trans-

verse series of longitudinal rods, whereupon logs to the depth of an additional five feet are put in place between the longitudinal series of vertical rods, whereupon other transverse rods and longitudinal rods are put in place, it being understood that whenever rods come in contact they are fastened together in some way, as by tying, soldering, riveting, brazing or welding. At suitable points the larger longitudinal rods 2' are put in place and the building up is continued until the desired amount of material is incorporated, whereupon the ends of the encircling rods, which have been extended from time to time by the addition of sections, are secured together so as to bind the outside layers as well as the inside portions together. A large part of the central portion of the raft may be made up of short timbers such as pit timbers, saw logs, lumber, etc., much of which would not be worth transporting by other means. If not timber but some other freight such as oil, etc., is to be transported, I weld plates over a similar framework and through it to the desired extent, forming compartments or tanks of suitable size, connecting with the upper part by suitable manholes or hatches.

With a timber transporter made up as above described there is little danger of the loss of timber, since even if the transporter should be torn asunder, it would break up into a plurality of sections, each of which would constitute a separate transporter and be recoverable as such. Even if the transporter was torpedoed, large portions of it would remain intact. The transporter may be constructed on land and afterward launched, or may be constructed upon the ice or in water. When it has reached its destination it affords a convenient means for storing a vast amount of timber until it is desired to use it, which timber can be removed by cutting away the transverse rods, as may be found to be necessary. The cutting of the encircling rods of a timber transporter would release but a relatively small portion of timber. The iron rods can be obtained at a minimum cost and when the timber is removed can be sold at a fair price 115 as scrap at the destination of the raft. The transporter is constructed of a shape such that it can be easily towed through the water. The proportions of the transporter and the sizes of the rods can of course be varied 120 as desired, care being taken that the rods be of sufficient size to safely stand the strain to which they may be subjected. The transporter is preferably made elliptical in cross-section. The upper ends of the vertical rods 125 can be bent over in opposite directions out of the way of the workmen while the timber is being put in place.

As will be evident, my invention permits of various modifications without departing 130

from the spirit thereof or the scope of the appended claims.

What I claim is:

1. In a freight transporter, the combination of a plurality of longitudinally extending series of vertical rods, a plurality of longitudinally extending series of horizontal rods, rods of said first mentioned series being secured to rods of said second mentioned series, a plurality of longitudinally extending rods constituting transversely extending series and vertically extending series and secured to rods of the two first mentioned series, the longitudinally extending series of vertical rods and the longitudinally extending series of horizontal rods forming longitudinal spaces for timber or other freight.

2. In a freight transporter, the combination of a plurality of longitudinally extending series of vertical rods, a plurality of longitudinally extending series of horizontal rods, rods of said first mentioned series being secured to rods of said second mentioned series, a plurality of longitudinally extending rods constituting transversely extending series and vertically extending series and secured to rods of the two first mentioned series, and a series of encircling rods, the longitudinally extending series of vertical rods and the longitudinally extending series of horizontal rods forming longitudinal spaces for timber or other freight.

3. In a freight transporter, the combination of a plurality of longitudinally extending series of vertical rods, a plurality of longitudinally extending series of horizontal rods, rods of said first mentioned series being secured to rods of said second mentioned series, a plurality of longitudinally extending rods constituting transversely extending series and vertically extending series and secured to rods of the two first mentioned series, and a series of encircling rods, the longitudinally extending series of vertical rods and the longitudinally extending series of horizontal rods and the encircling rods forming longitudinal spaces for timber or other freight.

4. In a freight transporter, the combination of a plurality of longitudinally extending series of vertical rods, a plurality of longitudinally extending series of horizontal rods, rods of said first mentioned series being secured to rods of said second mentioned series, a plurality of longitudinally extending rods constituting transversely extending series and vertically extending series and secured to rods of the two first mentioned series, and rods lying in a substantially vertical plane and disposed at an angle to the vertical rods and secured thereto, and longitudinally extending series of vertical rods and the longitudinally extending series of horizontal rods forming longitudinal spaces for timber or other freight.

5. In a freight transporter, the combination of a plurality of longitudinally extending series of vertical rods, a plurality of longitudinally extending series of horizontal rods, rods of said first mentioned series being secured to rods of said second mentioned series, a plurality of longitudinally extending rods constituting transversely extending series and vertically extending series and secured to rods of the two first mentioned series, the longitudinally extending series of vertical rods and the longitudinally extending series of horizontal rods forming longitudinal spaces for timber or other freight, some of the longitudinally extending rods having means for securing hawsers thereto.

6. In a freight transporter, the combination of a plurality of longitudinally extending series of vertical rods, a plurality of longitudinally extending series of horizontal rods, rods of said first mentioned series being secured to rods of said second mentioned series, a plurality of longitudinally extending rods constituting transversely extending series and vertically extending series and secured to rods of the two first mentioned series, horizontal plates and vertical plates connected to rods of said series and forming inclosing compartments.

IVAN ARKLEY BAYLEY.
